Patent expires December 13, 1964

3 Claims. (Cl. 57—121)

1

This invention relates to ring twisters. More particularly, it relates to a new and improved ring twister for continuous twisting.

In continuous ring twisting frames, a ring was centered about a bobbin positioned on a rotating spindle, and a traveller formed by bending a metal wire inwardly at both of its ends to provide hooks was disposed on the ring so that it could travel thereon. A thread, after passing axially through a guide, passed under the traveller and was then wound on the rotating bobbin. If the traveller were stationary, it would act merely as a guide and the thread would wind up on the bobbin without undergoing any twist. If the traveller had the same angular speed as the bobbin, the thread would be twisted but would not be wound on the bobbin. Owing to the slight friction of the traveller on the ring, the angular speed of the traveller was lower than that of the bobbin, with the consequence that the yarn was twisted as it was wound on the bobbin. In order to insure winding of the thread over the entire length of the bobbin, the ring was reciprocated in a vertical direction.

The above described ring twister has undergone only slight alteration. In general, the improvements consisted mainly in the form and shape of the ring and traveller. Generally, the traveller was disposed in a vertical plane inside of the ring, and attempts have been made to disposed the ring astride (in a horizontal plane) on the ring.

The above described ring twisters, though satisfactory for cotton and wool, were not satisfactory for use with artificial threads. In the twisting of synthetic yarns, such as rayon, it is essential that the thread be lubricated or dressed in order to impart flexibility and slip characteristics thereto. The dressing composition generally comprised a fatty compound which adhered to both the ring and traveller and was transferred into black coom under the effect of the small metal particles resulting from the abrasive action of the metal. Through projection, such coom stained the windings or "cop." Such defect was still further accentuated due to the lubrication of the ring itself. When the thread broke, the cop had a tendency to increase in size (expand) and the accumulation of the thread resulting therefrom resulted in an intense sweeping of the ring and traveller, with the result that the coom was projected on and stained the adjacent cops. Further, the expanded cop itself was stained. The stained cops were either rejected or the stained windings were removed, producing waste. Thus,

2

in general, the defects of the prior art ring twisters were the rejection of the cops due to staining and the waste resulting from removal of the stained yarn.

An object of this invention is to provide a new and improved ring twister.

Another object of this invention is to provide a ring twister for rayon having means for preventing staining of the thread.

Other and additional objects will become apparent hereinafter.

The objects of the invention are accomplished, in general, by securing the ring on which the traveller rides to the outside of a cylindrical shield centered and disposed in spaced relationship about a bobbin, whereby the lubricant or dressing of the yarn is inhibited from being projected onto the windings and, in the event the thread breaks and the cop expands, the thread will engage a clean surface. Means are also provided for the lubrication of the ring, and the shield is so constructed that it will receive any drippings and prevent them from being projected onto the thread.

The nature and objects of the invention will become apparent from the following detailed description when taken in connection with the accompanying drawings, wherein:

Figure 1 is a side elevation, partly in section, of one position of a ring twister frame embodying the features of the invention;

Figure 2 is a plan view of the ring and shield;

Figure 3 is a section taken on the line 3—3 of Figure 4; and

Figure 4 is an enlarged fragmentary detailed section of the shield, ring and traveller.

Referring to the drawings, wherein like reference numerals designate like parts, the reference numeral 1 designates a spindle provided with a pulley 2 whereby the spindle is rotated by a belt (not shown). The spindle 1 is provided with the usual support on which a bobbin 3 is disposed.

The reference numeral 7 designates a ring carrier formed of an aluminum or aluminum alloy cylinder which constitutes a shield and which, as shown in Figure 1, is centered about and disposed in spaced relationship to the bobbin. The ring carrier 7 is reciprocated axially of the bobbin in the well-known manner. A ring 8 is secured, as by hot pressing, adjacent the top of the shield 7. In the form shown, the ring 8 is provided with a boss 9 which is secured to the ring carrier 7. It is, of course, to be understood that the boss can be formed on the ring carrier

instead of on the ring. The boss 9 spaces the ring 8 from the ring carrier 7, forming a gutter 10 and annular space 10' and is provided with small vertically extending holes 11 for reasons which will become apparent.

The ring carrier 7 is provided with a shoulder 12 which is designed to engage the ring rail of the frame (not shown). The shoulder 12 is provided with a drip groove 13. At the bottom, the ring carrier 7 is provided with a flange having a drip groove 14 for receiving the lubricating oil which is introduced in small quantities in the gutter 10 and which oozes through the holes 11 and along the outside wall of the ring carrier.

The ring 8 is formed of hardened steel and is adapted to be traversed by a traveller, generally indicated by the reference numeral 15. The traveller 15 is formed of a metal wire which, in side elevation, has the shape of a C, the branches 16 and 17 thereof being hooked on the ring 8. The free terminal of the upper branch 16 is preferably bent into substantially U-shape, as indicated by the reference numeral 18, and the lower branch 17 terminates in a loop 19. It is to be noted that, as shown in Figure 3, the U 18 and the loop 19 are on opposite sides relative to the vertical member of the traveller 15. When the traveller 15 is in position on the ring 8, the upper branch 16 is disposed in the gutter 10 and the lower branch 17 is disposed in the annular space 10'.

As is shown in Figure 4, the construction of the traveller is such that it rests on the ring 8 along a curved surface of small extent and constant form, offering a minimum of resistance to friction.

Due to the form of the traveller, the thread can be easily threaded therethrough. When the ring twister is at rest in inoperative position, the traveller 15 hangs down by its weight and is suspended by the upper branch 16 on the ring 8 whereby the lower branch 17 is opened, i. e., spaced from the ring 8 and through which the thread is introduced.

In operation, the thread A, which is fed through a guide 6 positioned axially of the bobbin, passes beneath the upper branch 16, and pulls the traveller whereby the traveller is inclined so that it engages the ring at only two points, as shown in Figure 4, and reduces friction to a minimum. It is to be noted that during operation, the thread A does not engage the top edge of the shield. If desired, the top edge of the shield can be made slightly lower than the top edge of the ring.

Though the invention has been described in connection with the traveller being disposed in a vertical plane on the ring, the invention is not restricted thereto.

Since it is obvious that various changes and modifications may be made in the above description without departing from the nature or spirit thereof, this invention is not restricted thereto except as set forth in the appended claims.

We claim:

1. A ring twister comprising a cylindrical shield adapted to be centered about and disposed in spaced relationship about a bobbin on which the twisted yarn is wound, a ring secured to the outside of said shield, a boss spacing said ring from said shield and providing a gutter, said boss having small holes extending vertically therethrough, means to receive drippings from the outside of said shield, and a traveller slidably disposed on said ring.

2. A ring twister comprising in combination, a ring with a cylindrical interior shield adapted to be centered about and disposed in spaced relationship about a bobbin on which the twisted yarn is wound, an annulus spacing said ring from said shield and providing a channel at the top for grease or oil and an annular chamber at the bottom, a vertical traveller slidably disposed on the outside of said ring and having ends extending into said channel and said chamber respectively, said annulus having small substantially vertical apertures extending between said channel and said chamber for the passage of oil or grease to said chamber in a position to be picked up and distributed by the ends of said traveller for lubricating the contacting surfaces.

3. A ring twister, as set forth in claim 2, in which said traveller is in the shape of a C and the upper end thereof is bent sidewise into substantially U-shape and the lower end thereof terminates in a loop extending in a direction opposite to the U-shaped end and adapted to engage the inner surface of said ring during operation, the yarn passing through the apex of the upper bend of said traveller.
